Des. 641

William D. Sorton, of New York, N.Y.
Letters Patent No. 641. Dated April 25th, 1854.

• The schedule referred to in these Letters Patent, & making part of the same.

To all whom it may concern:

Be it known that I, William D. Sorton, of the City, County, and State of New York, have invented a new ornamental design for the fronts of clock cases, and I do hereby declare that the following is a full, clear, and exact description of the same, reference being had to the accompanying drawings forming a part of this specification, in which-

Fig. 1 is a front elevation.

Fig. 2, a vertical section through the center.

Fig. 3, a horizontal section in the red line shown in Fig. 1.
Similar letters of reference indicate like parts in

the several Figs.

This design is more particularly adapted for fronts of cast metal, but it is also capable of being manufactured in plastic materials. Its general character is Gothic, and its form that of a doorway or window.

The shafts A, A, at the sides are embellished with tracery, (a, a), (b), (c), (d, d), (e, e), (f) of the different descriptions common to the style, being supported by ornamental pedestals B, B, and surmounted by pinnacles C, C, ornamented with tracery (g, g).

The arch D, is internally ornamented with tracery (e, e), and above it is a cornice (f) extending across from near the crown of the arch to the shafts.

The panels between the arch and the cornice (f) are filled with perpendicular tracery (h, h) and above, the cornice is ornamented with tracery (k, k).

Over the crown of the arch, is a pinnacle, E, ornamented with tracery (h, h') and surmounted with an urn (i). On each shaft

Des. 641

A, there is an escutcheon (j).

The central part under the arch, and between the shafts, is filled in with paneling A. H. the lower part of which H, stands out in advance of G.

The design when made in cast iron, may be cast thin in all parts, as represented in the sections, Figs. 2 and 3.

What I claim as my invention, and desire to secure by Letters Patent, is

The design and configuration of the plate, represented in the accompanying drawings, and herein described, forming the front of a clock case.
